UNITED STATES PATENT OFFICE.

ROSCOE BEAN, OF BEREAL, OHIO.

TORPEDO-CANE.

No. 897,572.

Specification of Letters Patent.

Patented Sept. 1, 1908.

Application filed April 19, 1907. Serial No. 369,043.

To all whom it may concern:

Be it known that I, ROSCOE BEAN, a citizen of the United States, residing at Berea, in the county of Cuyahoga and State of Ohio, have invented certain new and useful Improvements in Torpedo-Canes, of which the following is a specification, reference being had therein to the accompanying drawings.

The present invention relates to torpedo canes.

The object of the invention is to provide an improved explosion device for a cane of this character, in which the explosion head can be readily secured to the plunger in such a manner as to allow the plunger a free reciprocating movement within the head; in which the passageway leading to the explosion chamber will be so constructed as to permit the escape of fragments of the torpedoes; which will be provided with an improved cut-off for controlling the passageway through which the torpedoes are fed from the magazine to the explosion chamber; and which will have an improved magazine supported upon the plunger and so constructed as to permit the same to be readily charged with torpedoes and to permit the escape of fragments of the torpedoes; thus providing an explosion device which will be more certain in its operation and which will not be liable to accidental discharge or to an explosion in the magazine or passageway.

With these objects in view my invention consists in certain novel features of construction and certain parts and combinations hereinafter to be described, and then more fully pointed out in the claims.

In the accompanying drawings, Figure 1 is a side elevation of a portion of a cane embodying my invention; Fig. 2 is a transverse section of the same on the line $x-x$ of Fig. 1 looking in the direction of the arrows; Fig. 3 is a front elevation of such a cane; and Fig. 4 is a rear elevation thereof partially in section; and Fig. 5 is a vertical sectional view of the explosion head and the lower portion of the plunger.

In these drawings, I have illustrated the preferred form of my invention and have shown the explosion device as consisting of an explosion head 1, having formed therein an explosion chamber provided at its lower portion with outlet apertures 2. This explosion head is also provided with a lateral extension 3, forming a conduit 4 adapted to receive the torpedoes from the passage con-

nected the same to the magazine, as herein-after described. The conduit 4 is open on its inner side and is adapted to be closed by the plunger 5, which, when in its lowermost position, entirely closes the conduit and prevents the escape of torpedoes therefrom, but, when in its uppermost position, is raised a sufficient distance above the bottom of the conduit to allow the escape of one or more torpedoes, as may be desired. This conduit is preferably provided with one or more slots and with an aperture 7 at the lowermost point of the outer wall thereof. This permits all dust or fragments which may be chipped from the torpedoes in their passage from the magazine to the explosion head to escape. The explosion head 1 is also provided on its opposite sides with lugs 8, which are capable of being bent inwardly to engage the grooves 9 in the plunger 5, which grooves extend from a point near the bottom of the plunger to a sufficient distance above the bottom thereof to permit the plunger to be moved downwardly a distance sufficient to bring the lower end into contact with the bottom of the explosion chamber. The upper portion of the plunger 5 is hollow, as shown at 10, and is adapted to receive and retain the lower portion of the cane proper 11. Rigidly secured to the plunger 5 and preferably formed integral with the upper part thereof is a magazine 12, which is preferably of a breadth considerably greater than the diameter of the plunger and may be provided on its opposite sides with slots or openings 13. This magazine is also provided with suitable inlet and outlet apertures, the outlet aperture communicating with the passage 14 extending diagonally through the plunger to the opposite side thereof and to a point adjacent to the upper end of the conduit 4 in the explosion head. The inlet aperture is provided with an outwardly extending lip 15, surrounding the lower portion thereof and adapted to form a guideway for the introduction of the torpedoes thereto. An opening or slot 16 of less width than the diameter of said outlet aperture is preferably provided in the outer wall of the magazine and extends from a point near the bottom thereof upwardly to the inlet aperture, thence outwardly through the lip 15 to a point near the outer edge thereof, as shown at 17, thus providing for the escape of any particles which may be broken from the torpedoes as they are fed into the magazine. That end of

the passageway 14 adjacent to the conduit 4 is normally closed by means of a suitable cut-off, which is adapted to be operated by the extension 3 of the explosion head to open 5 said passageway. This cut-off is here shown as consisting of a plate 18 reciprocably supported on the face of the plunger, and, when in its normal position, extending over the end of the passageway 14 and effectually closing 10 the same. This plate is preferably secured to the plunger by providing an elongated slot 19 in the plate, which slot extends from a point a short distance above the bottom thereof to a point near the upper end 15 thereof and is adapted to receive a lug 20 extending outwardly from the plunger, the T-shaped head of which extends over the edges of the slot when the plate is in its vertical position and serves to retain the same in its 20 proper relation with the plunger. The plate is retained in its vertical position by means of a screw 21, which extends through the slot 19 and enters the body of the plunger 5. The head of the screw being of greater diameter 25 than the breadth of the slot 19, it also serves to retain the plate in its proper relation to the plunger.

If desired, suitable means may be provided 30 for maintaining the plate in its lowermost position with the lower portion thereof closing the outlet of the passage 14. I have here shown such means, which consists of a coiled spring 22 having one end secured to the screw 21 and the opposite end secured to 35 the upper portion of the plate 18, thus holding the same normally in its lowermost position, but permitting it to move upwardly when the plunger is moved downwardly and the lower edge of the plate comes into contact 40 with the upper edge of the portion 3 of the explosion head.

The portion 3, which forms the conduit leading to the explosion chamber, preferably extends some distance above the body portion 45 of the explosion head and has its inner side open. The plunger 5 is provided at a point below the magazine with a rib 23 extending outwardly therefrom and for a portion of the distance about the same. This 50 rib serves both as a stop to prevent the excessive upward movement of the explosion head and to prevent the upward discharge of the gases and other products of the explosion. The plunger is also provided on each side 55 thereof with vertical ribs 24 extending preferably from the inner end of the rib 23 to a point near the lower end of the magazine and adapted to be engaged by the edges of the upper portion of the portion 3 of the explosion head and to coöperate with the lugs 8 60 engaging the grooves 9 in the plunger to hold the explosion head 1 and the plunger 5 in their proper relative positions.

Thus, it will be apparent that I have provided 65 an explosion device of the character

described, in which the operative parts are secured together by the bending of the lugs 8 into the grooves 9 of the plunger, thereby permitting the plunger to move relatively to the explosion head for a distance equal to the length of the groove; further, that I have, by providing the conduit in the explosion head and the magazine with apertures at all points where dust or fragments of torpedoes might accumulate, afforded means for the escape of these fragments, thereby minimizing the liability of an explosion in said chamber or magazine; and further, that I have provided an improved cut-off, which normally extends across the feed passage from the magazine and serves to prevent the escape of the torpedoes from said passage into the explosion head, but which is engaged by the explosion head and moved out of alignment with said passage on each downward stroke of the plunger, thereby feeding a torpedo, for each downward stroke of the plunger.

I wish it to be understood that I do not desire to be limited to the exact details of construction shown and described, for obvious modifications will occur to a person skilled in the art.

Having thus fully described my invention, what I claim as new and desire to secure by Letters Patent, is:—

1. A device of the character described comprising an explosion head, a plunger adapted to reciprocate therein, a magazine carried by said plunger provided with an outlet and having an opening of less width than the diameter of said outlet extending from the point near the bottom of said magazine, and means for feeding the contents of said magazine to said explosion head.

2. A device of the character described comprising an explosion head, a plunger adapted to reciprocate therein, a magazine carried by said plunger provided with an outlet on one side thereof and having a slot extending upward from a point near the bottom of said magazine on the side opposite said outlet, and means for feeding the contents of said magazine to said explosion head.

3. A device of the character described comprising an explosion head, a plunger adapted to reciprocate therein, a magazine carried by said plunger and provided with an inlet opening and an outlet opening, a lip extending outwardly beneath said inlet opening, a slot formed in said magazine and extending from a point near the bottom thereof to said inlet opening, thence outwardly to a point near the outer end of said lip, and means for feeding the contents of said magazine to said explosion head.

4. A device of the character described comprising an explosion head, a magazine, a plunger reciprocably mounted in said explosion head having a passage extending

transversely thereof and adapted to connect said magazine with said explosion head, and a cut-off carried by said plunger, extending across one end of said passage and adapted 5 to be engaged by said head and moved out of alinement with said passage when said device is operated.

5. A device of the character described comprising an explosion head, a magazine, a 10 plunger reciprocably mounted in said explosion head and having a passage extending transversely thereof and adapted to connect said magazine with said explosion head, and a plate carried by said plunger, extending 15 across one end of said passage and adapted to be engaged by said head and moved out of alinement with said passage when said device is operated.

6. A device of the character described 20 comprising an explosion head, a magazine, a plunger reciprocably mounted in said explosion head and having a passage therein adapted to connect said magazine with said explosion head, a headed lug carried by said 25 plunger, and a plate having a slot adapted to receive said headed lug, whereby said plate is reciprocably held on said plunger and adapted to close said passage and to be engaged by said head and moved out of alinement with said passages.

7. A device of the character described comprising an explosion head, a magazine, a plunger reciprocably mounted in said explosion head and having a passage extending 35 transversely thereof and adapted to connect said magazine with said explosion head, a plate carried by said plunger, extending across one end of said passage and adapted to be engaged by said head and moved out of 40 alinement with said passage, and a spring for holding said plate normally in its lowermost position.

8. In a device of the character described, the combination, with a plunger and an 45 explosion head, of a conduit leading to the lower portion of said explosion head extend-

ing at an angle thereto and having an aperture in the bottom thereof.

9. In a device of the character described, the combination, with a plunger and an explosion head, of a conduit leading to the lower portion of said explosion head, having its lower end extending at an angle thereto and having an aperture through the bottom 50 wall thereof. 55

10. In a device of the character described, the combination, with a plunger having a magazine formed integral therewith, a passageway extending through said plunger and connected at one end to said magazine, and a 60 cut-off for controlling said passage, of an explosion head inclosing the lower end of said plunger and forming an explosion chamber, said chamber having a lateral extension forming a conduit adapted to receive the tor- 65 pedoes from said passageway and conduct the same to the lower portion of said explosion head, said extension having an aperture through the lower wall thereof.

11. In a device of the character described, the combination, with a plunger having a passageway extending therethrough, a magazine formed integral with said plunger and having an outlet communicating with said passageway, an aperture near the bottom of 75 said magazine, and a cut-off for controlling said passage, of an explosion head having an enlarged portion forming an explosion chamber and adapted to receive the lower end of 80 said plunger and having a laterally reduced portion forming a conduit adapted to receive ammunition from said passageway and convey the same to the explosion chamber, said laterally extending portion having an aperture through the lower portion thereof. 85

In testimony whereof, I affix my signature in presence of two witnesses.
